UNITED STATES PATENT OFFICE.

ARTHUR A. JOHNSON, OF NEW YORK, N. Y., ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,332,342.

Specification of Letters Patent.

Patented Mar. 2, 1920.

Application filed May 17, 1918. Serial No. 235,147.

To all whom it may concern:

Be it known that I, ARTHUR A. JOHNSON, a citizen of the United States, residing in borough of the Bronx, in the county of the Bronx, city and State of New York, have invented certain new and useful Improvements in Combined Typewriting and Computing Machines, of which the following is a specification.

This invention relates to combined typewriting and computing machines, and more particularly to the kind which not only compute in vertical columns but also crosswise of said columns. It embodies features similar to those shown and described in my pending application Serial No. 232,746, filed May 6, 1918.

This invention is shown as applied to a machine of the type in which there are provided two computing units, namely, a column-computing unit and a cross-computing unit. The column-computing unit usually comprises a relatively stationary actuator, which is traversed by one or more column-totalizers, the latter having computing wheels which are engaged *seriatim* by a master wheel in said actuator. For this relative travel the column-totalizers are secured to the typewriter carriage. The cross-computing unit also has a relatively stationary actuator; and a totalizer, comprising computing wheels, is mounted on a sub-carriage which is picked up and caused to travel intermittently with the typewriter carriage, so that the computing wheels may be engaged *seriatim* by the driving means of said actuator.

In such machines, the numbers written in different columns are computed additively in the totalizers at the respective columns. It is, however, sometimes desired to compute the numbers written in one or more columns subtractively in the cross-totalizer. This usually necessitates the reversing of the driving mechanism associated with the cross-computer when the carriage enters such a computing zone. This reversing of the driving mechanism is usually accomplished by the shifting of gears relatively to each other. With this method of reversing the driving mechanism, the teeth of the gears sometimes get out of alinement during the shifting of said gears, thus causing difficulty in connecting them.

An object of this invention is to provide

means for rendering the cross-totalizer effective additively or subtractively, when it is picked up to traverse a computing zone, without causing a change in the driving mechanism, thus eliminating any possible occurrence of the aforesaid difficulty.

This may be done in this type of machine, by providing two master wheels, in the actuator of the cross-computing unit, arranged adjacent to each other, and caused to rotate in opposite directions by a train of mechanism extending from the master wheel of the column-computing unit. When the cross-totalizer is rendered effective additively, the computing wheels thereof are moved into effective relation with one of the master wheels *seriatim* as the carriage passes through the computing zone. This may be done by a projection on a column-stop of the typewriter carriage which engages with a pick-up hook extending from a train of pick-up mechanism connected to the cross-totalizer.

If the cross-totalizer is to be rendered effective subtractively when the typewriter carriage passes through a computing zone, the pick-up hook is engaged by a projection on the column-stop which is offset a distance equal to a half letter-space relative to the body of the stop, thus causing the computing wheels of the cross-totalizer to move to positions one-half letter-space to one side of the positions which they occupy when the cross-totalizer is rendered effective additively. The computing wheels consequently are brought into effective relation *seriatim* with the other master wheel associated with the cross-computing unit.

With this arrangement, it will be seen that in order to have the cross-totalizer compute either additively or subtractively, it is not necessary to reverse the action of the driving mechanism for the computing wheels, but that there are two master wheels provided which are caused to rotate in opposite directions, and that the computing wheels may be moved into effective relation with either master wheel.

Other features and advantages will hereinafter appear.

In the accompanying drawings,

Figure 1 is a side elevation of an Underwood typewriting machine, showing my invention applied thereto, some of the parts being broken away.

110

Fig. 2 is a front view of the machine.

Fig. 3 is a fragmentary rear view, showing the pick-up mechanism for the cross-totalizer. The typewriter carriage in this figure is passing through a computing zone, with the cross-totalizer connected thereto.

Fig. 4 is a fragmentary top view, showing the locking pawls for the sub-carriage or cross-computer carriage.

10 Fig. 5 is a perspective view of a portion of the stop-bar, showing two column-stops thereon, one being set so that it will act as an addition pick-up element, and the other being set so that it will act as a subtraction pick-up element.

I have shown my invention as applied to an Underwood machine, in which alphabet keys 10 and numeral keys 11 swing key-levers 12 to rock bell-crank 13 about a fulcrum rod 14, to swing type-bars 15 upwardly and rearwardly about a fulcrum 16, to cause types 17 to strike against the front side of a platen 18. The platen 18 is mounted on a carriage 19 which travels on a front rail 20 and a rear rail 21.

For its letter-feeding movements, the carriage 19 is provided with a rack-bar 22, which meshes with a pinion 23 to rotate the latter by means of a spring drum 24 connected to the typewriter carriage. The pinion 23 is connected to rotate an escapement wheel 25 by the usual pawls (not shown). The escapement wheel 25 is provided with teeth 26, which coöperate with a loose dog 27 and a fixed dog 28 on a dog-rocker 29, when the latter is vibrated by a universal bar 30 engaged by heels 15^a of the type-bars 15. The upper end of the dog-rocker is returned to its forward or normal position 40 by the usual springs (not shown).

The computing mechanism in part may be similar to that shown in the application of Henry L. Pitman, Serial No. 186,098, filed August 14, 1917.

45 The numeral keys 11 operate a master wheel 31 contained within a casing 32, and for this purpose, each numeral key has secured thereto a cam plate 33. These cam plates 33 have cam-slots 34 which vary in 50 shape with the numeral keys, and when any numeral key is depressed its cam will strike and swing a universal bail 35, which forms part of a differentially rocking frame 36. Said frame is given a differential motion by 55 the various cams 33. These movements are transferred to the master wheel 31 as follows: The bail 35, it will be noted, is at the bottom of the machine, whereas the master wheel 31 is near the top of the machine, and 60 the differential motion is carried from the bottom of the machine to the top by a link 37 which is connected to the frame 36, so that the link is differentially vibrated by the depressions of the different numeral keys.

65 The connections between the link 37 and

the master wheel 31 may be identical with those shown in the application of Pitman herein referred to, and include a rock-arm 38 to which the link 37 is pivotally connected, said rock-arm being fast to a rock shaft 70 40, which carries a second rock-arm 41 contained within the casing or actuator 32, with the result that the vertical vibration of the link 37 rocks the rock-arm 41 forwardly and rearwardly, so that a link 42, pivotally 75 connected thereto, will vibrate a rack bar 43, which engages a barrel pinion 44 fixed to a gear 45 meshing with a pinion 46. Secured to one side of the pinion 46 is another pinion 47, which meshes with and drives a 80 pinion 48 secured to a shaft 49 to which the master wheel 31 is secured, thus rotating the master wheel additively in a clockwise direction. The connections are such that the rack bar 43 normally engages the pinion 44, and that depression of any numeral key will cause the rack bar to drive forwardly to an extent depending on the numeral key depressed.

To transfer the number to dial wheels 50 90 of any one of a plurality of column-totalizers 51, the master wheel 31 operates said dial wheels 50 *seriatim* through gear wheels 52 and intermediate pinions 53; each pinion 53 meshing with a computing wheel 54 95 to form a connection with a carry-over mechanism comprising a wheel 55, which also serves as a locking wheel mounted on a swinging lever 56, as shown in the application of Walter Wright, Serial No. 708,090, 100 filed July 8, 1912.

Each coupler wheel 55 is journaled on a swinging lever 56 pivoted on a rod 57 extending lengthwise of the totalizer, which swinging lever is normally drawn forward 105 by means of a spring 58, so as to cause the idler coupling wheel 55 to normally mesh with its computing wheel 54, as described in said Wright application.

Each swinging lever 56 is provided with 110 a cam-faced projection 60 to be struck by a finger 61 on a shaft 62, so as to swing the idler coupling wheel clear of its computing wheel, said finger 61 having at its inner end a pawl 63 which coöperates with a rack 64 on 115 a computer carriage 65, which travels on a guide-rail 66, thus locking the carriage against movement during a computing operation. The totalizers may be adjustably secured to the computer carriage in any convenient manner and travel relatively to the master wheel 31, so that the gear wheels 52 may be brought into coöperative relation *seriatim* with the master wheel as the typewriter carriage passes through a computing 125 zone.

To actuate the shaft 62 and thus render the finger 61 and the locking pawl 63 effective every time a number is transferred to the totalizer, each numeral key 11 is pro- 130

vided with a cam 67, which engages a universal bar 68, forming part of a bail 70, to swing the latter about its pivot 71, during the early part of the depression of the key 5 and prior to transferring the number to the dial wheel. The bail 70 has an upwardly extending arm 72, which engages with a downwardly projecting arm 73 secured to the shaft 62 to rock the latter and thus actuated 10 the finger 61 and pawl 63.

The master wheel 31 may be caused to rotate subtractively (counter-clockwise). For this purpose the gear 45 may occupy two positions, that of addition, Fig. 2, and 15 that of subtraction. To set the mechanism of the actuator 32 so that the master wheel 31 may be rotated subtractively by the rack 43, the barrel pinion 44 and the large gear 45 are moved together rightwardly from the 20 Fig. 2 position as a unit; the barrel pinion 44 being maintained in meshing relation with the rack 43, while the gear 45 shifts from engagement with the pinion 46 and into engagement with the pinion 48. If the 25 rack 43 is now actuated, the gear 45 will drive the pinion 48 directly, and thus cause the master wheel to rotate subtractively. To obtain this shifting of the gear 45, a shaft 74, on which it is secured, is mounted 30 for sliding movement in the direction of its length (Fig. 2). This shaft 74 is provided with a grooved collar 75 engaged and moved by an arm 76 on a shaft 77, which is rocked through the intermediary of another arm 78 35 on the shaft; said arm 78 being swung by an arm 80 secured to a shaft 81, which may form part of the bichrome shift mechanism common to Underwood typewriters. The forward end of said shaft 77 is provided 40 with a double key lever 82 having an addition key 83 and a subtraction key 84 thereon, as shown in Fig. 2, the latter key being actuated to set the actuator to subtraction. When it is again desired to compute additively, the addition key 83 is actuated, thus 45 setting the gear 45 back to the Fig. 2 position. A suitable detent 85 may be provided to hold the mechanism controlled by the keys 83 and 84 in its shifted positions.

To rapidly position the carriage 19 and a column-totalizer 51 in a computing zone, there is provided a series of tabulator keys 86, which, when depressed, swing levers 87 about a fulcrum 88 to move plungers 90 50 against the tension of return springs 91, to bring the upper ends thereof into the path of column-stops 92 on a stop-bar 93 secured to the typewriter carriage by brackets 94. The usual rack-releasing means (not shown 55 in the drawings) may be actuated by any one of the plungers 90 to effect the releasing of the typewriter carriage 19 by raising the rack 22 out of engagement with the escape- 60 ment pinion 23 at the proper time. The usual spring drum 24, after the release of

the carriage, moves the carriage on its rails to the left until it is arrested by one of the column-stops 92 coming into engagement with the projected plunger 90. The tabulator key is then permitted to return to normal 70 position, thus effecting a reengagement between the feed rack 22 and the pinion 23.

In addition to the column-totalizers 51 there is also provided a cross-totalizer 95 to effect the cross-computing of numbers written in several columns. This may be done by any addition master wheel 96 or a subtraction master wheel 97, both contained within an actuator 98. The master wheels 96 and 97 are caused to rotate in opposite 75 directions, and may be connected to the master wheel 31 of the column-computing unit to be driven therewith by means which may comprise a suitable train of mechanism extending from the master wheel 31, and including the horizontal shaft 74, which, through bevel gears 100 and 101, drives a vertical shaft 102, the latter being connected by means of bevel gears 103 and 104, to drive a shaft 105, which may be connected 80 to drive the master wheels 96 and 97. The shaft 105 ordinarily drives the addition master wheel 96 in a clockwise direction by means of a gear 106 on the shaft 105; said gear meshing with an intermediate pinion 95 107 having a pinion 108 secured to the side thereof, the latter meshing with a pinion 109 fixed to a shaft 110 to which the addition master wheel is also secured. Another gear 111 on the shaft 105 is provided to mesh 100 with a pinion 112, which is like the pinion 108 but secured to a shaft 113 to which the subtraction master wheel 97 is secured. It will be seen that by thus connecting shaft 105 with the master wheels 96 and 97, they may 105 be rotated in opposite directions.

The movements of the master wheels 96 and 97 may be transferred to the cross-totalizer 95, through the intermediary of a series of gear wheels 114, to a series of dial wheels 115 contained within the cross-totalizer 95. The cross-totalizer 95 may be adjustably mounted on a supporting bar or cross-computer carriage 116, which may be intermittently connected (in a manner which will 110 be presently described) to move with the typewriter carriage 19 when any one of the column-totalizers 51 passes through a computing zone. To guide the cross-computer carriage 116 in its traveling movement, a 115 suitable guide-rail 117 may be provided.

The cross-totalizer 95 may be connected to be advanced and returned during the travel of the typewriter carriage by a horizontal lever 118, which may be operated to rock 125 about a vertical axis 120 by a vertically disposed lever 121, a projection 118^a on the lever 118 engaging in a slot 119 of the lever 121 to form a connection between said levers. The lever 121 swings about a pivot 122, and 130

has pivotally connected thereto at its upper end a pick-up bar 123, which may be picked up by certain of the stops 92, which engage with a hook-like portion 124 on said bar 123 and move the bar step by step with the advancing movement of the carriage 19. This train of mechanism, including the parts 118, 121 and 123, may act in an advancing direction against the tension of a spring 125 (Fig. 3), which quickly returns the cross-totalizer or jumping totalizer 95 when the hook 124 is disconnected from one of the stops which picked it up. This disconnection may be accomplished by a pin 129 on the bar 123, 15 said pin engaging with a cam 126 to move the hook 124 out of engagement with the column-stop 92.

Each column-stop 92 is provided with two lugs, an addition lug 127 and a subtraction lug 128. When the numbers written in the column, at which a column-stop is set, are to be computed additively in the cross-totalizer, the column-stop is so placed that the addition lug 127 may engage with the pick-up bar 123. Thus, the gear wheels 114 of the cross-totalizer are brought into co-operative relation with the addition master wheel 96 *seriatim*, as the typewriter carriage passes through the computing zone. The subtraction master wheel 97 at this time may rotate idly between the adjacent gear wheels 114.

When the numbers written in any column are to be computed subtractively in the cross-totalizer, the column-stop is so adjusted in that column that the subtraction lug 128 thereof may engage with the pick-up bar. It will be seen that the subtraction lug 128 is offset a distance equal to half a letter-space relative to the addition lug 127 which is in alignment with the body of the column-stop 92. Thus, when the pick-up bar is engaged by a subtraction lug, the gear wheels 114 of the cross-totalizer 95 will be moved *seriatim* into effective relation with the subtraction master wheel 97, at which time the addition master wheel may rotate idly between the adjacent gear wheels 114.

From the foregoing, it will be understood that the cross-totalizer may be moved additively or subtractively, and that such movements are predetermined by normal and displaced projections or lugs on the column-stops of the typewriter carriage.

To accurately align and hold the cross-totalizer during computing operations, I have preferably provided two racks 130 and 131, which may be engaged by pawls 132, 133, respectively. When the cross-totalizer is rendered effective additively and a number is transferred to the dial wheel 115, the pawl 132 is caused to engage between the teeth of its associated rack 130. This is done by the arm 134 projecting rearwardly from the rock shaft 62 which carries the locking pawl

63 for the column-computer carriage 65. Said arm 134 is connected by means of a link 135 to a similar arm 136 projecting rearwardly from a shaft 137 to rock the latter, and, through the intermediary of springs 138 and 139, to swing pawls 132 and 133, respectively. The pawl 133, however, will strike on the teeth of its associated rack bar 131, and thus be prevented from entering between the teeth which are staggered relatively to the teeth of the rack 130. With this rack-and-pawl construction, the teeth can be at least a letter-space distance apart, although the cross-totalizer may be held at intervals equal to one-half letter-space distances apart.

When, however, the cross-totalizer is rendered effective subtractively, the pawl 133 during computing operations is caused to engage between the teeth of its associated rack 131, while the pawl 132 will strike idly on the teeth of its associated rack and cause its associated spring 138 to be flexed.

The springs 138 and 139 associated with the pawls 132 and 133 are normally under no tension, Fig. 1, but may be tensioned by being moved in either direction. The free ends of said springs may be connected to their associated pawls in any convenient manner, and in this way the springs may assist in retracting the pawls from between the teeth of their associated racks, should there be any tendency for said pawls to stick therebetween, the pawls being loosely mounted on the shaft 137.

A finger 140, similar to the finger 61, may be secured to the shaft 137 to perform a similar function for the cross-totalizer as that described for the column-totalizer 51.

It may be desired at times to reverse the direction of rotation of the master wheels 96 and 97, so that the addition master wheel may subtract and the subtraction master wheel may add. This may be desired for the purpose of making corrections, as, for example, if, after the column-totalizer has traversed the computing zone, the operative discovers an error in the number written. To correct this error, the operative reverses the direction of rotation of the master wheels and permits the totalizer to again traverse the computing zone, while the erroneous number is again typed, but at this time it causes a reverse computation, thus clearing the totalizer of the erroneously computed number.

To reverse the direction of rotation of the master wheels 96, 97, Fig. 2, the subtraction key 84 may be actuated, thus causing the shaft 74 to slide lengthwise to take the bevelled gear 100 out of mesh with the gear wheel 101 on the vertical shaft 102, and cause a gear wheel 141 secured to the shaft 74 to mesh with the gear wheel 101. Thus, if the shaft 74 is now rotated, the shafts 102 130

and 105 will be rotated in a reverse direction; consequently, the master wheels 96 and 97, geared to the shaft 105, will also be rotated in a reverse direction. It will be seen that when the gear wheel 141 is shifted into meshing relation with the gear wheel 101, the gear wheel 45 will also be shifted and brought into meshing relation with the pinion 48, thus reversing the direction of rotation of the master wheel 31 of the column-computing unit, and consequently causing the erroneously written number when typed again to be also taken out of the column-totalizer 51.

15 It will be understood that the column-totalizers and the cross-totalizer may be alike in construction, and that they may be of any convenient form in which there is a relative traveling movement between the totalizer and the master wheel. It should also be understood that the driving mechanism for the master wheels may be of any convenient form, but preferably as shown and described in the drawings.

25 Variations may be resorted to within the scope of the invention, and portions of the improvement may be used without others.

Having thus described my invention, I claim:

30 1. The combination with a typewriter carriage, of a cross-totalizer, and means to cause said cross-totalizer to travel intermittently with said typewriter carriage, said means comprising displaced adjustable devices on said typewriter carriage which determine whether said cross-totalizer should be rendered effective additively or subtractively.

2. The combination with a typewriter carriage, of a plurality of column-totalizers adapted to travel therewith, driving means for said column-totalizers, a cross-totalizer, pick-up means to cause said cross-totalizer to travel intermittently with said typewriter carriage, driving means for said cross-totalizer, and a train of mechanism extending to the latter from the driving means associated with the column-totalizers, said pick-up means comprising displaced adjustable devices on said carriage which cause the cross-totalizer to be rendered effective additively or subtractively.

3. In a combined typewriting and computing machine, the combination with a typewriter carriage and a reciprocatory computing element, of a pair of master wheels, a set of numeral keys, connections whereby said keys turn the master wheels simultaneously in opposite directions, and a pick-up mechanism for said reciprocatory computing element including means for bringing different master wheels into use in different computing zones.

4. In a combined typewriting and computing machine, the combination with a typewriter carriage and a jumping totalizer

or element, of a pair of master wheels, a set of numeral keys, connections whereby said keys turn the master wheels simultaneously in opposite directions, a pick-up mechanism for said totalizer including means for bringing different master wheels into use in different computing zones; said means including a rack, and lugs adjustable on said rack, certain of said lugs having offset portions, and a hook device to engage said lugs and connected with said jumping totalizer.

5. In a combined typewriting and computing machine, the combination with a typewriter carriage and a jumping totalizer or element, of a pair of master wheels, a set of numeral keys, a pick-up mechanism for said totalizer including means for bringing different master wheels into use in different computing zones, a valuating mechanism operable by said keys and connected to one of said master wheels, and a reversing device connecting said valuating mechanism to the other of said master wheels.

6. In a combined typewriting and computing machine, the combination with a typewriter carriage and a jumping totalizer or element, of a pair of master wheels, a set of numeral keys, a pick-up mechanism for said totalizer including means for bringing different master wheels into use in different computing zones, a valuating mechanism operable by said keys and connected to one of said master wheels, and a reversing device connecting said valuating mechanism to the other of said master wheels; said master wheels being placed closely side by side to permit either one to turn idly between the adjacent computing wheels, while the other is operating one of said computing wheels.

7. In a combined typewriting and computing machine, the combination with a typewriter carriage and a jumping totalizer or element, of a pair of master wheels, a set of numeral keys, connections whereby the master wheels when actuated will turn simultaneously in opposite directions, a pick-up mechanism for said totalizer or element, including means for bringing different master wheels into use in different computing zones, a valuating mechanism operable by said keys and connected to one of said master wheels, said master wheels placed closely side by side to permit either one to turn idly between adjacent computing wheels, while the other is operating one of said computing wheels, and means for reversing the direction of rotation of said master wheels simultaneously at will.

8. In a combined typewriting and computing machine, the combination with a typewriter carriage and a jumping totalizer or element, of a pair of master wheels, a set of numeral keys, connections whereby the

master wheels when actuated will turn simultaneously in opposite directions, a pick-up mechanism for said totalizer or element, including means for bringing different master wheels into use in different computing zones, a valuating mechanism operable by said keys and connected to one of said master wheels, said master wheels placed closely side by side to permit either one to 10 turn idly between the adjacent computing wheels, while the other is engaged with one of said computing wheels, a column-totalizer, a reversible master wheel therefor, and means for reversing at will the rotation of 15 all of said master wheels simultaneously.

9. In a combined typewriting and computing machine, the combination with a typewriter carriage and a jumping totalizer or element, of a pair of master wheels, a set 20 of numeral keys, connections whereby the master wheels when actuated will turn simultaneously in opposite directions, a pick-up mechanism for said totalizer including means for bringing different master wheels 25 into use in different computing zones, said means including a rack coöperative with said carriage, lugs adjustable on said rack, certain of said lugs having offset portions, a hook device to engage said lugs and connected with said jumping totalizer, a valuating mechanism operable by said keys and 30 connected to one of said master wheels, said master wheels being placed closely side by side to permit either one to turn idly between the adjacent computing wheels, while the other is engaged with one of said computing 35 wheels, and a rack-and-dog-mechanism for accurately positioning the jumping totalizer or element at every computing operation.

10. In a combined typewriting and computing machine, the combination with a typewriter carriage and a jumping totalizer or element, of a pair of master wheels, a set 40 of numeral keys, connections whereby the master wheels when actuated will turn simultaneously in opposite directions, a pick-up mechanism for said totalizer including means for bringing different master wheels 45 into use in different computing zones, said means including a rack coöperative with said carriage, lugs adjustable on said rack, certain of said lugs having offset portions, a hook device to engage said lugs and connected with said jumping totalizer, a valuating mechanism operable by said keys and 50 connected to one of said master wheels, said master wheels being placed closely side by side to permit either one to turn idly between the adjacent computing wheels, while the other is engaged with one of said computing 55 wheels, and a rack-and-dog-mechanism for accurately positioning the jumping totalizer or element at every computing operation.

11. In a combined typewriting and computing machine, the combination with a typewriter carriage and a jumping totalizer or element, of a pair of master wheels, a set 60 of numeral keys, connections whereby the master wheels when actuated will turn simultaneously in opposite directions, a pick-up mechanism for said totalizer including means for bringing different master wheels 65 into use in different computing zones, said means including a rack coöperative with said carriage, lugs adjustable on said rack, certain of said lugs having offset portions, a hook device to engage said lugs and connected with said jumping totalizer, a valuating mechanism operable by said keys and 70 connected to one of said master wheels, said master wheels being placed closely side by side to permit either one to turn idly between the adjacent computing wheels, while the other is engaged with one of said computing 75 wheels, and a rack-and-dog-mechanism for accurately positioning the jumping totalizer or element at every computing operation, said rack-and-dog-mechanism including a pair of dogs, one of which is effective only at the adding operation, and the other of which is effective only at the subtraction operation.

12. In a combined typewriting and computing machine, the combination with a typewriter carriage and a jumping totalizer or element, of a pair of master wheels, a set 80 of numeral keys, connections whereby the master wheels when actuated will turn simultaneously in opposite directions, a pick-up mechanism for said totalizer including means for bringing different master wheels 85 into use in different computing zones, said means including a rack coöperative with said carriage, lugs adjustable on said rack, and certain of said lugs having offset portions, a hook device to engage said lugs and connected with said jumping totalizer, valuating mechanism operable by said keys and 90 connected to one of said master wheels, said master wheels being placed closely side by side to permit either one to turn idly between the adjacent computing wheels, while the other is engaged with one of said computing 95 wheels, and a rack-and-dog-mechanism for accurately positioning the jumping totalizer or element at every computing operation, said rack-and-dog-mechanism including a pair of dogs, one of which is effective only at the adding operation, and the other of which is effective only at the subtraction operation, a spring device being provided for engaging the dog-and-rack-devices.

13. In a combined typewriting and computing machine, the combination with a typewriter carriage and a jumping totalizer or element, of a pair of master wheels, a set 100 of numeral keys, connections whereby the master wheels when actuated will turn simultaneously in opposite directions, a pick-up mechanism for said totalizer including means for bringing different master wheels 105 into use in different computing zones, said means including a rack coöperative with said carriage, lugs adjustable on said rack, certain of said lugs having offset portions, a hook device to engage said lugs and connected with said jumping totalizer, a valuating mechanism operable by said keys and 110 connected to one of said master wheels, said master wheels being placed closely side by side to permit either one to turn idly between the adjacent computing wheels, while the other is engaged with one of said computing 115 wheels, and a rack-and-dog-mechanism for accurately positioning the jumping totalizer or element at every computing operation, said rack-and-dog-mechanism including a pair of dogs, one of which is effective only at the adding operation, and the other of which is effective only at the subtraction operation, means being provided 120

125

- for automatically engaging and disengaging the dog-and-rack-devices.
13. In a combined typewriting and computing machine, the combination with a typewriter carriage and a jumping totalizer or element, of a pair of master wheels, a set of numeral keys, connections whereby the master wheels when actuated will turn simultaneously in opposite directions, a pick-up mechanism for said totalizer including means for bringing different master wheels into use in different computing zones, said means including a rack co-operative with said carriage, lugs adjustable on said rack, certain of said lugs having offset portions, a hook device to engage said lugs and connected with said jumping totalizer, a valuating mechanism operable by said keys and connected to one of said master wheels, said master wheels being placed closely side by side to permit either one to turn idly between the adjacent computing wheels, while the other is engaged with one of said computing wheels, and a rack-and-dog-mechanism for accurately positioning the jumping totalizer or element at every computing operation, said rack-and-dog-mechanism including a pair of dogs, one of which is effective only at the adding operation, and the other of which is effective only at the subtraction operation, places being provided whereby the depression of any key effects co-operation of the rack-and-dog elements.
14. In a combined typewriting and computing machine, the combination with a typewriter carriage and a jumping totalizer or element, of a pair of master wheels, a set of numeral keys, a pick-up mechanism for said totalizer or element, including means for bringing different master wheels into use in different computing zones, said pick-up mechanisms including a rack co-operative with said carriage, lugs adjustable on said rack, certain of said lugs having offset portions, a hook device to engage said lugs and connected with said jumping totalizer, a valuating mechanism operable by said keys and connected to one of said master wheels, a reversing mechanism driven by said valuating mechanism connected to the other of said master wheels, said master wheels being placed closely side by side to permit either one to turn idly between adjacent computing wheels, while the other is driving one of said computing wheels, a column-totalizer, a reversible master wheel therefor, means for reversing at will the direction of rotation of all of said master wheels simultaneously, and a rack-and-dog-mechanism for accurately positioning the jumping totalizer at the computing operation, said rack-and-dog-mechanism including a pair of dogs, one of which is effective only at the adding operation, and the other of which is effective only at the subtraction operation; a spring device being provided for engaging the dog-and-rack-devices; means being provided whereby the depression of any key effects co-operation of the rack-and-dog-devices.
15. In a combined typewriting and computing machine, the combination of a pair of master wheels, a set of numeral keys, connections whereby said keys turn the master wheels simultaneously in opposite directions, and a pick-up mechanism including means for bringing different master wheels into use automatically in different computing zones.
16. In a combined typewriting and computing machine, the combination of a pair of master wheels, a set of numeral keys, connections whereby said keys turn the master wheels simultaneously in opposite directions, and a pick-up mechanism including means for bringing different master wheels into use automatically in different computing zones, said means including half-spaced lugs.
17. In a combined typewriting and computing machine, the combination of a pair of master wheels, a set of numeral keys, connections whereby said keys turn the master wheels simultaneously in opposite directions, a pick-up mechanism including means for bringing different master wheels into use automatically in different computing zones, said means including half-spaced lugs, and a hook device to engage said half-spaced lugs and co-operating with said master wheels.
18. In a combined typewriting and computing machine, the combination of a pair of master wheels, a set of numeral keys, connections whereby said keys turn the master wheels simultaneously in opposite directions, a pick-up mechanism including means for bringing different master wheels into use automatically in different computing zones, said means including half-spaced lugs, and a hook device to engage said half-spaced lugs and co-operating with said master wheels, said master wheels placed closely side by side to permit either one to turn idly between the adjacent computing wheels, while the other is engaged with one of said computing wheels.
19. The combination of a carriage, a cross-totalizer adapted to travel intermittently with said carriage, said totalizer comprising computing wheels, an actuator therefor, said actuator comprising two master wheels, one for addition and one for subtraction, and means for automatically rendering said cross-totalizer effective either additively or subtractively.
20. The combination of a carriage, a cross-totalizer comprising computing wheels, an actuator therefor, said actuator compris-

ing two driving elements, and means including column-stops on said carriage for automatically rendering said cross-totalizer effective, either additively or subtractively, 5 relative to said driving elements.

21. The combination of a cross-totalizer, a typewriter carriage, means to cause said totalizer to travel intermittently with said carriage when the latter passes through a 10 computing zone, two master wheels for said totalizer, said master wheels being adapted to rotate in opposite directions, and means on said typewriter carriage to cause said totalizer to traverse the computing zone either 15 additively or subtractively.

22. The combination of a cross-totalizer, a typewriter carriage, a sub-carriage for said cross-totalizer, means to cause said sub-carriage and totalizer to travel intermittently with said typewriter carriage when the latter passes through a computing zone, two master wheels for said totalizer, said master wheels being adapted to rotate in opposite directions, and means on said typewriter carriage to cause said totalizer to traverse the computing zone either additively or subtractively.

23. The combination of a cross-totalizer comprising computing wheels, an actuator therefor, said actuator comprising two master wheels, one for addition and one for subtraction, and means for automatically rendering said cross-totalizer effective either additively or subtractively, including column-stops on the typewriter carriage effective to bring the computing wheels into effective relation *seriatim* with one of said master wheels during an additive computation, and other column-stops on said typewriter carriage to bring said computing wheels into effective relation with the other master wheel *seriatim* when a subtractive computation is taking place.

24. The combination of a cross-totalizer comprising computing wheels, an actuator therefor, said actuator comprising two master wheels, one for addition and one for subtraction, and means for automatically rendering said cross-totalizer effective either additively or subtractively, including column-stops on the typewriter carriage effective to bring the computing wheels into effective relation *seriatim* with one of said master wheels during an additive computation, other column-stops on said typewriter carriage to bring said computing wheels into effective relation with the other master wheel *seriatim* when a subtractive computation is taking place, and means to cause 60 each of said master wheels to be reversely rotated.

25. The combination of a typewriter carriage, a cross-totalizer comprising computing wheels, two relatively fixed master wheels placed adjacent to each other, nu-

meral keys, means controlled by said numeral keys to cause said master wheels to rotate in opposite directions so that addition may be performed by one master wheel and subtraction by the other master wheel, pick-up means to cause said cross-totalizer to travel intermittently with said typewriter carriage, and column-stops on said typewriter carriage, said column-stops having addition lugs and subtraction lugs thereon 75 adapted to engage with said pick-up means, to render said totalizer effective either additively or subtractively.

26. The combination of a cross-totalizer comprising computing wheels, a typewriter carriage, two relatively fixed master wheels placed adjacent to each other, numeral keys, means controlled by said numeral keys to cause said master wheels to rotate in opposite directions so that addition may be performed by one master wheel and subtraction by the other master wheel, pick-up means to cause said cross-totalizer to travel intermittently with said typewriter carriage, and column-stops on said typewriter carriage, 90 said column-stops having addition lugs and subtraction lugs thereon adapted to engage with said pick-up means, each addition lug being in alignment with the body of its associated column-stop and effective to bring 95 the computing wheels into effective relation with the addition master wheel, each subtraction lug being offset relatively to the body of its associated column-stop an amount equal to the distance from the center of one master wheel to the center of the other master wheel.

27. The combination of a totalizer, a carriage, numeral keys, said totalizer comprising computing wheels, co-axially mounted 105 master wheels, mechanism between said numeral keys and said master wheels to rotate said master wheels in opposite directions, one for addition and one for subtraction, means to cause said totalizer to traverse the 110 computing zone either additively or subtractively, and manually-controlled means for changing the connections of the mechanism between said keys and said master wheels to reverse the direction of rotation 115 of said master wheels, so that the addition master wheel may be rotated subtractively and the subtraction master wheel may be rotated additively.

28. The combination of a totalizer, a carriage, numeral keys, said totalizer comprising computing wheels, co-axial master wheels, mechanism between said numeral keys and said master wheels to rotate said master wheels in opposite directions, one for 125 addition and one for subtraction, means to cause said totalizer to traverse the computing zone either additively or subtractively, manually-controlled means for changing the connections of the mechanism between said 130

keys and said master wheels to reverse the direction of rotation of said master wheels, so that the addition master wheel may be rotated subtractively and the subtraction master wheel may be rotated additively, and a column-computing unit comprising a totalizer and a master wheel, said master wheel being driven by said keys, and said manually-controlled means being also effective to reverse the direction of rotation of said last-mentioned master wheel.

29. The combination of a totalizer comprising computing wheels, a carriage with which said totalizer is adapted to travel, and an actuator for said totalizer, said actuator comprising a main shaft, two gears on said main shaft, two master wheels, and two individual shafts, one for each master wheel, each shaft having a pinion thereon, one of said pinions meshing directly with one of said gears, the other pinion being geared to the other gear by means of an intermediate pinion.

30. The combination of a carriage, a cross-totalizer adapted to travel intermittently with said carriage, said totalizer comprising computing wheels, an actuator therefor, said actuator comprising driving mechanism, means for automatically rendering said totalizer effective either additively or subtractively, and locking means comprising two pawls, one of said pawls being rendered effectively while the totalizer passes additively through a computing zone, the other pawl being rendered effective when said totalizer passes subtractively through the computing zone.

31. The combination of a carriage, a cross-totalizer adapted to travel intermittently with said carriage, said totalizer comprising computing wheels, an actuator therefor, said actuator comprising driving mechanism, means for automatically rendering said totalizer effective either additively or subtractively, locking means comprising two pawls, one of said pawls being rendered effective while the totalizer passes additively through a computing zone, the other pawl being rendered effective when said totalizer passes subtractively through the computing zone, said pawls being loosely mounted on a rock-shaft, springs on said rock-shaft having a yielding connection with said pawls, and a rack member with which said pawls may effectively engage one at a time.

32. The combination of a typewriter carriage, a cross-totalizer comprising computing wheels, an actuator therefor, said actuator comprising two master wheels, one for addition and one for subtraction, means for automatically rendering said cross-totalizer effective either additively or subtractively, including column-stops on the typewriter carriage effective to bring the computing wheels into effective relation *seriatim*

with one of said master wheels during an additive computation, other column-stops on said typewriter carriage to bring said computing wheels into effective relation with the other master wheel *seriatim* when a subtractive computation is taking place, a rack member, and two pawls, said pawls engaging one at a time between the teeth of said rack member, one during the additive computation, the other during a subtractive computation.

33. The combination of a typewriter carriage, a cross-totalizer comprising computing wheels, a cross-totalizer carriage, two relatively fixed master wheels placed adjacent to each other, numeral keys, means controlled by said numeral keys to cause said master wheels to rotate in opposite directions, so that addition may be performed by one master wheel and subtraction by the other master wheel, pick-up means to cause said cross-totalizer carriage to travel intermittently with said typewriter carriage, column-stops on said typewriter carriage, said column-stops engaging with said pick-up means to render said totalizer effective either additively or subtractively, and locking means comprising a rack member on said cross-totalizer carriage and two pawls, said pawls being under the control of said keys, one of said pawls being rendered effective while the totalizer passes additively through a computing zone, the other pawl being rendered effective when the totalizer passes subtractively through the computing zone.

34. In a combined typewriting and computing machine, the combination with a typewriter carriage, of a cross-totalizer, mechanism for actuating said cross-totalizer when the latter travels past the former, and means to cause said cross-totalizer to travel with said carriage when the totalizer is passing through computing zones, including means to vary the letter-space positions assumed by the cross-totalizer in passing through a computing zone, and thereby to determine whether said totalizer is to be effective additively or subtractively.

35. In a combined typewriting and computing machine, the combination with a typewriter carriage, of column-totalizers traveling therewith, driving means for said column-totalizers, a cross-totalizer, driving means adapted to operate said cross-totalizer additively or subtractively, a train of mechanism extending to the latter from the driving means for said column-totalizers, and pick-up means whereby said carriage may effect a relative traveling movement between said cross-totalizer and the driving means therefor, said pick-up means comprising settable devices to determine additive or subtractive operation of said cross-totalizer.

36. In a computing machine, the combination with a totalizer having computing

wheels at letter-space intervals, of two co-
5 axial master wheels spaced at half a letter-
space interval, connections between said
master wheels to cause simultaneous rota-
tion thereof in opposite directions, and
means effecting a relative step-by-step letter-
space movement between said totalizer and
said master wheels, to bring either of said
master wheels and successive wheels of said
10 totalizer into alignment, the additive or sub-
tructive character of the computation being
determined by the master wheel in effective
relation with said computing wheels in such
step-by-step movement.

15 37. In a typewriting and computing ma-

chine, the combination with a traveling car-
riage, of a cross-totalizer, mechanism for
actuating said cross-totalizer, and carriage-
actuated pick-up means to cause a relative
step-by-step letter-space movement of said 20
totalizer and said actuating mechanism past
each other, including means for varying the
letter-space positions of said totalizer and
said actuating mechanism relatively to each
other, and thereby determining additive or 25
subtractive operation of said totalizer.

ARTHUR A. JOHNSON.
